UNITED STATES PATENT OFFICE

2,523,901

PUMP MEANS

Charles F. Degner, Chicago, Ill.

Application September 30, 1948, Serial No. 52,089

2 Claims. (Cl. 103—225)

1

The present invention relates to pump means or the like, particularly for pumping liquids, as from wells, such as deep wells or the like.

Among the objects of the invention is to provide novel means for lifting a fluid or liquid from a well, or the like, which is self-contained and protected and which acts directly for best and most efficient results.

A further object of the invention is to provide novel means for sealing the relatively moving parts of the pump whereby the greater the load stress, the more efficient is the sealing means.

Other objects, capabilities, advantages, features and the like are comprehended by the invention as will later appear, and as are inherently possessed by the invention.

Referring briefly to the drawings:

Fig. 1 is a view in part elevation and in part section of an embodiment of the invention;

Fig. 2 is a fragmentary, vertical, sectional view on an enlarged scale of the device;

Fig. 3 is a transverse sectional view taken in a plane represented by line 3—3 in Fig. 2 of the drawings;

Fig. 4 is a transverse sectional view taken in a plane represented by line 4—4, Fig. 2 of the drawings;

Fig. 5 is a fragmentary vertical sectional view of the structure shown in Fig. 2;

Fig. 6 is a horizontal sectional view of a powering means for operating the pump;

Fig. 7 is a vertical sectional view taken in a plane represented by a line 7—7 in Fig. 6 of the drawings;

Fig. 8 is a vertical sectional view, with a part in elevation, of a slightly alternative form of pump means;

Fig. 9 is a transverse sectional view taken in a plane represented by a line 9—9 in Fig. 8 of the drawings;

Fig. 10 is a fragmentary elevational view of an operative part of a pump means, on an enlarged scale; and

Fig. 11 is a similar view showing parts in section.

Referring more in detail to the drawings, the embodiments selected to illustrate the invention are shown in association with a well cylinder 1 surmounted by a cap 2 as at the top of the ground 3, the cap 2 having a depending hub 4 to which is fixed, as by screws 5 (see Fig. 7), the upper end of a pump delivery channel 6 connected at its lower end by suitable coupling means or the like 7 to the upper end of a pump barrel or cylinder 8 extending down in the well cylinder 1.

2

At the lower end of the cylinder 8 is any suitable strainer or the like 9, and in the lower end of the cylinder 8 is a suitable inlet valve means 10 which may be of the check valve type, for effecting entry and flow or lifting of liquid from the lower portion of the well cylinder 1 upwardly into the pump cylinder 8.

Within the pump cylinder 8 is vertically reciprocable a plunger piston means 11, as shown in Fig. 8, or a plunger piston means 12, as shown in Figs. 1—5 of the drawings, which is suitably connected with the lower end of a plunger rod 13 which extends and passes upwardly through the device as later more fully explained.

On the well cap 2 is a pump gearing housing 14 (see particularly Figs. 6 and 7) in which is rotatably mounted to rotate about a vertical axis a worm gear 15 as in a ball bearing means or the like 16, which gear is operatively engaged with a driving worm 17 having a shaft 18 to the outer end of which is fixed a pulley or the like 19 over which runs a driving belt or the like 20 from a motor pulley or the like 21 fixed to a shaft 22 of a motor 23 suitably supported on the ground 3 (see Fig. 1) or a suitable base or floor 24 (see Figs. 8 and 9).

Upon the housing 14 is a pedestal member 25 having a base footing 26 suitably set or fixed to the top part of the housing 14, the member 25 having a suitable socket for a portion of the ball bearing means 16, and the member 25 may be of any desired cross-sectional form, as square, or round, or the like as desired. To the member 25 is fixed, as by screws or the like 27, the lower end of an upwardly extending elongated channel or housing 28 having at its upper end a head cap 29. See Figs. 8 and 11 in particular.

The pedestal member 25 has a boring 30 downwardly in which extends the lower end portion 31 of a double screw actuator member 32 extending upwardly in the housing 28 and having a hub portion 33 at the upper end of the member 32 in the cap 29 (see Fig. 8). The lower portion 31 of the member 32 has a splined connection with a hub portion 35 of the gear 15, and the portion 31 has a downwardly extending sleeve 36 in the well cap 2, for slidably guiding the plunger rod 13.

On the double threaded portion of the actuator 32 is operatively associated a cross-head 37 internally formed to operatively fit with the double threaded part of the actuating member 32. To the end portions of the cross-head 37 are connected the lower ends of slide rods 38 and 39, the upper ends of which extend through and are

slidably reciprocable through and in the end portions of the cap 29 and at the upper and outer end portions of these rods 38 and 39 is fixed a cross-head 40. The upper end of the plunger rod 13 is fixed by suitable connecting means 41 to the central portion of the cross-head 40 so that the cross-head will reciprocate with the rods 13, 38 and 39. The upper end portion or hub 33 of the double screw actuator member 32 is rotatable in the cap 29 and to the upper end part 42 (see Figs. 10 and 11) of the part 33 is suitably secured a step or thrust bearing part 43 so that the double screw actuator may turn or rotate relative to the cap part 29, but the plunger rod 13 only slides through the central bore 44 of the parts 32, 33 and 42.

The double screw actuator 32 has a set of races 45 of slow pitch (see Figs. 10 and 11) so that as the cross-head 37 is raised thereby, as the actuator 32 rotates, it will move upwardly slowly as the plunger piston means 11 or 12 raises the liquid; and has a set of races 46 of fast pitch so that as the cross-head 37 is caused to descend thereby as the actuator 32 rotates, it will move downwardly quickly and, hence, the plunger piston means 11 or 12 moves downwardly likewise quickly in the liquid in the pump cylinder 8.

The plunger piston means, as 11 or 12, may be of the particular construction shown in Figs. 1, 2, 3, 4 and 5. Such means comprises a flanged head 47 and a tubular body 48 the upper end of which has a valve port 49 controlled by a valve 50. On the flanged part 47 is a cup-shaped sealing means 51, the cylindrical wall of which sealingly and slidably contacts the inner wall of the pump cylinder 8, and the upper portion of the sealing means 51 has a bevelled lip or rim or the like 52 and cooperative with the same is a wedge ring 53 having a tapered surface or face 54 cooperative with the bevelled surface 52 to force and maintain the cylindrical wall of the member 51 in sealing contact with the inner wall of the pump cylinder 8.

Within the ring 53 and between it and the tubular body part 48 is a keeper ring 55 which also has a bevelled or wedge part 56 acting against a ring 53 to maintain the latter stressed against the tapered or wedge part 52 of a sealing cup 51.

The wider part of the ring 53 has a depression or depressions 53^a, 53^b, or grooves or the like, for aiding the sealing effect of said ring 53, on cup 51. The keeper ring 55 is forced down or stressed by a second cup shaped sealing means 57 which is pressed down by the base or skirted portion 58 of a valve case or cage 59 threaded to the threaded portion 60 of the tubular body part 48. The upper rim portion of the sealing cup 57 has a tapered part or wedge part 61 against which is stressed the lower tapered or wedge rim portion 62 of a follower or keeper 63 having a top part 64 against which is stressed a coil spring 65 compressed under a cross pin or the like 66 in the plunger rod 13. The wedge parts 61 and 62 act to maintain the wall of the cup 57 in sealing contact with the wall of the pump cylinder 8. The top part 64 has a bore or throat 67 for upward passage of liquid when the plunger piston means is forced down in the liquid column in the pump cylinder 8.

The valve cage 59 has suitable side openings 68 also for passage of the liquid from the valve

port 49 to and through the bore or throat 67, and also has a top 69 to which the lower end of the plunger rod 13 is suitably fixed. When the rod 13 is reciprocated on a down stroke, liquid is forced upwardly by way of the tubular member 48, valve port 49, openings 68, and bore 67 thence into the cylinder 8, and on the up-stroke the valve 50 closes and the liquid above it is moved upwardly in the cylinder 8 to and through a piston type of wall 73 provided in the upper part of the cylinder 8, and thence by way of the pipe 70 (see Fig. 7) connected at its lower end to the wall 73 and in communication with the chamber of cylinder 8, the pipe 70 extending up through the chamber 6 and in communication with duct 71 provided in the hub 4, and thence by way of a delivery pipe 72.

In operation the motor 23 operates through the belt 20 to the worm 17 and the gear 15 to rotate the actuator 32. The latter causes a reciprocation of the cross-head 37 and hence the rods 38 and 39 and the cross-head 40. The latter causes a reciprocation of the plunger rod 13 and hence the plunger piston means 11 or 12 and hence the liquid in the well 1 is lifted and forced out by way of the delivery or discharge duct 72. On the up-stroke of the plunger piston means 12, the force or weight of the liquid forces the wedge parts 52 and 53, as also the wedge parts 61 and 62, to maintain a liquid-tight seal of the cup members 51 and 57 with the wall of the pump cylinder 8. If these wedge parts wear, there is an automatic take up in compensation of any such wear so that the complete and efficient sealing effect will be maintained.

While I have herein described and upon the drawings shown an illustrative embodiment or embodiments of the invention, it is to be understood that the invention is not limited thereto but comprehends other constructions, details, arrangements of parts, features, and the like without departing from the spirit of the invention.

Having thus disclosed the invention, I claim:

1. A pump comprising a cylinder, piston means in the cylinder, a sealing means surrounding said piston means and having a yielding annular portion for sealingly and slidably contacting said cylinder during reciprocation of said piston means in the cylinder, and provided with a tapered surface portion on its upper inner face, a wedge-shaped solid ring surrounding and slidably on the piston and having a tapered portion cooperating with the tapered portion on the sealing means, said ring being provided with a depression on its upper surface thereby aiding the sealing effect of the sealing means.

2. A pump means as set forth in claim 1, and wherein said depression is in the form of a groove.

CHARLES F. DEGNER.
